(57) **CLAIM**

The ornamental design for a fluid mover enclosure, as shown and described.

DESCRIPTION

FIG. 1 is a front perspective view of a fluid mover enclosure showing our new design;

FIG. 2 is a top plan view of the fluid mover enclosure shown in FIG. 1;

FIG. 3 is a bottom plan view of FIG. 1;

FIG. 4 is a right side view of FIG. 1;

FIG. 5 is a left side view of FIG. 1;

FIG. 6 is a front view of FIG. 1;

FIG. 7 is a back view of FIG. 1;

FIG. 8 is a perspective view of the fluid mover enclosure, wherein the enclosure is shown assembled within an environmental mounting; and,

FIG. 9 is a perspective view of the fluid mover enclosure, showing the environmental mounting exploded around the enclosure.

The broken lines illustrate environment and form no part of the claimed design.
